UNITED STATES PATENT OFFICE.

ARTHUR REGINALD ANGUS, OF WESTMINSTER, LONDON, ENGLAND.

CONTROL OF TRAINS.

Original application filed December 22, 1921, Serial No. 524,228, and in Australia December 13, 1921.

Divided and this application filed September 1, 1925. Serial No. 53,814.

The invention forming the subject-matter of the present application for Letters Patent, which is a division of my application for Letters Patent Serial No. 524,228 filed 5 22nd December, 1921, relates to electrical train-controlling apparatus of the type in which a warning operation and a stopping operation are successively produced on a train in the first and second sections respectively of three consecutive sections of track when it is dangerous for the train to travel along the third section.

Apparatus of the aforesaid type according to the invention comprises on a train electro-responsive means adapted when energized by a current of a first or normal strength to give clearance to the train and when energized by a current of a second strength to cause the production of a warning operation on the train and adapted to be caused by the cessation of either of the said currents without the production of the other thereof to bring about the production of a stopping operation on the train and receiving means arranged to be in energizable relation to running rails alone and adapted to be caused by currents of two specific different strengths therein to energize the electro-responsive means by currents of the said first and second strengths respectively, and, on the track and in connection with three consecutive sections thereof in which the rails of each section on each side of the track are electrically continuous and the rails of each section on one side of the track are separated from adjacent rails by insulation, current-supplying means for supplying the running rails with which the said receiving means is arranged to be in energizable relation on the said one side of the track in the first of the three sections with currents of the said two specific different strengths and in the second of the three sections with current of the one of the said specific different strengths corresponding to current of the said first strength, traffic-controlling means pertaining to the second and third sections and adapted (a) in a position corresponding to the clear condition of both the second and third sections to cause the current-supplying means to supply the rails on the said one side of the first section with current of the one of the said specific different strengths corresponding to current of the said first strength, (b) in a position corresponding to

the clear condition of the second section and the danger condition of the third section to cause the current-supplying means to supply the rails on the said one side of the first section with current of the one of the said 60 specific different strengths corresponding to current of the said second strength, and (c) in a position corresponding to the danger condition of the third section to cause the current-supplying means not to supply the 65 rails on the said one side of the second section with current of either of the said specific different strengths.

For the purpose of adapting the apparatus to enable trains to protect themselves 70 automatically against being run into by following trains I employ as the traffic-controlling means pertaining to the second and third sections traffic-controlling electro-responsive means connected with the rails of 75 the second and third sections respectively and adapted to be energized only by current from a track-current-supplying means for supplying the rails on both sides of the second and third sections respectively with current that differs from the currents supplied by the first mentioned current-supplying means but to be short-circuited from the track-current-supplying means by conductively connected wheels of a railway vehicle 80 in the second and third sections respectively. 85

In order to provide for the case of the running of trains at different times in opposite directions on a single track, the track apparatus is adapted to be adjusted for the 90 running of trains in opposite directions so that by its adjustment for one or the other direction of running trains can at will be given protection against being run into from behind in either direction.

The invention, which comprises the various features defined in the claiming clauses hereof, is illustrated by the accompanying drawings, which represent examples of apparatus according thereto.

Figs. 1 and 1^A together show one example of track apparatus;

Fig. 2 shows train apparatus suitable for use with the track apparatus illustrated by Figs. 1 and 1^A;

Figs. 3 and 1^A together show another example of track apparatus; and

Fig. 4 shows train apparatus suitable for use with the track apparatus illustrated by Figs. 3 and 1^A together.

105

110

In each of the examples of track apparatus represented by Figs. 1 and 1^A and by Figs. 3 and 1^A, the track is divided by insulations as shown into sections I, II, III, IV, and V, of which section I is a terminal section, and each section has connected to its running rails traffic-controlling electro-responsive means constituted by two track relays connected to the two ends respectively of the corresponding sections and adapted to be energized only by continuous direct current supplied by a source 500 connected to the rails of the corresponding section and to be short-circuited by the presence of conductively connected wheels of a railway vehicle on the corresponding section; the track relays of section I have coils 518 and 528, those of section II have coils 541 and 545, those of section III have coils 558 and 562, those of section IV have coils 575 and 579, and those of section V have coils 592 and 596.

To set the track apparatus to enable a train to travel in the down direction (which is from section I towards section V) and protect itself in the rear from collision, the signalman moves a switch arm 503 (Fig. 1 or 3) to the right, bringing insulated contacts 502 and 524 carried by but insulated from the switch arm 503 into contact with contacts 504 and 523 respectively. Current then passes from the source 500 by way of a wire 501, the contacts 502 and 504, a wire 505, a branch wire 506, and branch wires 507 and 508 to a coil 509, thence by way of a wire 510 from the middle point of the coil 509 to the middle point of a coil 511, thence by way of wires 512 and 513 (from the respective extremities of the coil 511) and a wire 514 to rails 515 at a position midway of section I; thence current passes (a) along the rails 515 to a point near an insulation 516 to the left end of section I, thence by way of a wire 517, the coils 518, and a wire 519 to rails 520 at a point opposite to the insulation 516, and thence by way of wires 521 and 522, the contacts 523 and 524, and a wire 525 back to the source 500, and (b) along the rails 515 in the other direction to a point near an insulation 526 which separates section I from section II, thence by way of a wire 527, the coils 528, and a wire 529 to the rails 520 at a point opposite to the insulation 526, and thence by way of the rails 520 and the wire 521 to the source 500.

The coils 509 and 511 and the wires 507, 508, 510, 512, and 513 constitute a reactance joint which will allow the passage of continuous unidirectional current but will prevent (to a great extent if not wholly) in the known way the passage of pulsating unidirectional or alternating current. Similar reactance joints are provided for the other sections—namely, for section II, coils 533 and 535, and the wires 531, 532, 534, 536, and 537; for section III, coils 550 and 552 and

wires 548, 549, 551, 553, and 554; for section IV, coils 567 and 569 and wires 565, 566, 568, 570, and 571; and for section V, coils 584 and 586 and wires 582, 583, 585, 587, and 588. In the example the track relays of each section are polarized and the armature of each of them is adapted to take up a mid-position when the corresponding coils are deenergized and is adapted to take up different positions according to the directions of the continuous direct currents supplied to the corresponding coils and to take part in closing by means of contacts a particular circuit or particular circuits according to its position.

Current from the wire 505 similarly passes through the apparatus of the several sections II, III, IV, and V by way of branch wires 530, 547, 564, and 581 respectively and returns by way of the wire 521.

When all the sections I, II, III, IV, and V are unoccupied by any train the track relays relating to these sections, if all is in order and the switch arm 503 has been moved into such a position that it permits current to pass in the direction hereinbefore indicated, move their armatures into particular positions on the right side in which they take part in closing the circuits hereinafter described.

Train apparatus suitable for use in conjunction with the track apparatus shown in Figs. 1 and 1^A will hereinafter be described with reference to Fig. 2 and train apparatus suitable for use in conjunction with the track apparatus shown in Figs. 3 and 1^A will be hereinafter described with reference to Fig. 4; such apparatus is adapted when energized by current of a predetermined normal strength to cause the restraint of both a warning operation and a stopping operation, when energized by current of a predetermined lower strength to cause the restraint of a warning operation only, and when not energized to allow the production of both a warning operation and a stopping operation on the train. If it is desired that a train so equipped should travel along section I towards section V and the sections II and III ahead of the train are unoccupied by any other train and all is in order, the switch arm 503 having been moved to the right as hereinbefore described, the coils 558 and 562 of section III and the coils 541 and 545 of section II are energized and their respective armatures are in such positions as to enable current for affecting the apparatus on the train to flow in the manner now to be described.

In the case of the track apparatus illustrated by Figs. 1 and 1^A, a switch arm 605 is moved to the right to bring its insulated contacts 604 and 627 into contact with contacts 606 and 677 respectively, and current passes from the positive pole of a source 602

of unidirectional pulsating current by way of a wire 603 and the contacts 604 and 606, thence to the contacts 677 and 627 by way of the path hereinafter described, and back to the source 602 by way of a wire 628. In the case of the track apparatus illustrated by Figs. 3 and 1^A, a switch arm 605 is moved to the right to bring its insulated contacts 704 and 727 into contact with contacts 603 and 677 respectively, and current passes from a source 702 of alternating current of a particular frequency by way of a wire 703 and the contacts 704 and 606, thence to the contacts 677 and 727 by way of the path now to be described, and back to the source 702 by way of a wire 728. In both cases the current passes from contact 606 to contact 677 by way of a wire 607 (Figs. 1 and 3), a branch wire 608 (Fig. 1^A), a contact 609 and an insulated contact 610 on the armature 611 of the track relay 562 (the contacts 609 and 610 being in contact when the track relay 562 has been duly energized so as to move the armature 611 to the right), a wire 612, an insulated contact 613 on the armature 614 of the track relay 558, a contact 615 (the contacts 613 and 615 being in contact when the track relay 558 has been duly energized so as to move the armature 614 to the right), a wire 616, a contact 617, an insulated contact 618 on the armature 619 of the track relay 545 (the contacts 617 and 618 being in contact when the track relay 545 has been duly energized so as to move the armature 619 to the right), a wire 620, an insulated contact 621 on the armature 622 of the track relay 541, a contact 623 (the contacts 621 and 623 being in contact when the track relay 541 has been duly energized so as to move the armature 622 to the right), and a wire 624 to the track rails 515 near the insulation 516, thence along the track rails 515 of section I to a point near the insulation 526, and thence by way of wires 625 and 626 to the contact 677. Current is thus supplied to the track rails 515 of section I, and, as the wire 612 short-circuits a resistance 629, its strength is such that both warning and stopping operations are restrained on the train on rails 515. If, however, section III is occupied by a train and section II is unoccupied, the track relays of section III are de-energized, but the track relays of section II are energized; current consequently now passes from the source 602 (Fig. 1) or the source 702 (Fig. 3) to the contact 609 as before described, but owing to the de-energization of the track relays of section III the wire 612 is disconnected and consequently does not short-circuit the resistance 629, so that current passes from contact 609, by way of the resistance 629, to the contact 615 and thence to the rails 515 of section I and back to the source 602 (Fig. 1) or 702 (Fig. 3) along the path hereinbefore described. The current from the source 602 (Fig. 1) or 702 (Fig. 3) to the track rails 515 of section I is now, owing to its passage by way of the resistance 629, of such a strength that a warning operation is effected on the train occupying section I, and, if the driver causes the train to pass over the insulation 526 and enter section II, a stopping operation is produced on the train because the energization of the track relays 558 and 562 of section III, the energization of which is necessary for the supply of any current to a train on section II, since, the return from the rails 539 of section II to the source 602 (Fig. 1) or 702 (Fig. 3) being by way of a wire 645 connected to the wire 626, current from the source 602 or 702 can flow to the rails 539 only by way of a wire 630 (Fig. 1^A) connected to the wire 607, and a contact 631, then either by way of an insulated contact 632 on the armature 633 of the track relay 579 of section IV, a wire 634, an insulated contact 635 on the armature 636 of the track relay 575 of section IV, and a contact 637, the track relays 579 and 575 being energized and consequently the contacts 632 and 635 in contact with the contacts 631 and 637 respectively, or by way of a resistance 646 and the contact 637, the track relays 575 and 579 being de-energized, thence by way of a wire 638, a contact 639 and an insulated contact 640 on the armature 611 of the track relay 562 of section III only if the track relay 562 is energized, a wire 641, an insulated contact 642 on the armature 614 of the track relay 558 of section III, and a contact 643 only if the track relay 558 is energized, and a wire 644. In order that current of a normal strength should be supplied to section II for a train seeking to run thereon towards section V, the sections III and IV ahead of that train should be unoccupied by any other train and all should be in order. Suppose a train in section II is running in the direction towards section V. If sections III and IV are unoccupied current passes from the wire 607, by way of the wire 630 (Fig. 1^A), the contact 631, the insulated contact 632 on the armature 633 of the track relay 579 of section IV (the contacts 631 and 632 being in contact when the track relay 579 has been duly energized so as to move the armature 633 to the right), the wire 634, the insulated contact 635 on the armature 636 of the track relay 575, the contact 637 (the contacts 635 and 637 being in contact when the track relay 575 is duly energized so as to move armature 636 to the right), the wire 638, the contact 639, the insulated contact 640 on the armature 611 of the track relay 562 of section III, the wire 641, the insulated contact 642 on the armature 614 of the track relay 558 of section III, the contact 643, and the wire 644, to rails 539 of section II, thence

along the rails 539 to a point near insulation 543, thence by way of the wire 645 to the wire 626, and back to the source 602 (Fig. 1) or 702 (Fig. 3) along the path hereinbefore described. This current being of normal strength, warning and stopping operations are restrained on the train in section II. If, however, section III is unoccupied by another train but section IV is occupied by another train, a warning operation is produced on the train on passing into and along section II, and if the last mentioned train enters section III in spite of this warning it is stopped in section III because the de-energization of the track relays 575 and 579 of the occupied section IV breaks the circuit of the train clearance current, which, just as in the case described of the passage of the train through sections I and II, includes contacts on the armatures of the track relays of the next succeeding section. The strength of the current supplied to section II when section IV is occupied by another train is determined by the resistance 646 (then no longer short-circuited) connecting together the two contacts 631 and 633 of the relays 579 and 575 respectively of section IV; the current from the source 602 (Fig. 1) or 702 (Fig. 3) then flows by way of the resistance 646 to the contact 637 and thence back to the source 602 (Fig. 1) or 702 (Fig. 3) by way of the path hereinbefore described. Similar operations are effected as the train proceeds along successive sections.

To set the track apparatus to enable a train to run in the up direction—i. e., the direction from section V to section I—the switch arm 503 is moved to the left to bring its insulated contacts 502 and 524 into contact with contacts 598 and 599 respectively and thus to reverse the direction of the current passing to all the track relays, the armatures of which are consequently moved to the left to complete corresponding connections to the pertinent section or sections ahead of the train so as either to give it clearance along a section or first to allow a warning operation to be effected and afterwards to allow a stopping operation to be effected on the train as described with reference to travel in the down direction, the switch arm 605 being in this case moved to the left, and the clearance current supplied to the rails thus being, in the case of the track apparatus illustrated by Figs. 1 and 1^A, in the direction opposite to that of the current supplied to enable a train to travel in the down direction, or, in the case of the track apparatus illustrated by Figs. 3 and 1^A, of a frequency (from a source 602) that differs from that of the current supplied by the source 702 to enable a train to travel in the down direction. The apparatus on a train for use with the track apparatus illustrated by Figs. 1

and 1^A is adapted as hereinafter described to give clearance for either of the two directions only when energized by current of the direction appropriate to the direction of travel, and the apparatus on a train for use with the track apparatus illustrated by Figs. 3 and 1^A is adapted to give clearance for either of the two directions only when receiving current of the frequency appropriate to the direction of travel. In the case of a train travelling along section II in the up direction the connections are such that a warning operation is not produced on the train in section II if section I is unoccupied notwithstanding that there is no section in advance of section I through the armatures of whose track relays the current would according to the arrangements of the other sections have to pass. The connections for the up direction of travel for allowing a train to enter section I are shown in Figs. 1 and 1^A and Figs. 3 and 1^A but need not be further described. To enable a train to proceed in the up direction along section I, on entering which it would otherwise be stopped, the switch arm 605 must be moved so as to bring its insulated contacts 604 and 627 (Fig. 1), or 804 and 827 (Fig. 3), into contact with contacts 674 and 676 respectively, so that in the case of the apparatus illustrated by Fig. 1 the current passes from the negative pole of the source 602, or in the case of the apparatus illustrated by Fig. 3 the current passes from the source 802, by way of the wire 628, the contacts 627 and 676 (Fig. 1), or the contacts 827 and 676 (Fig. 3), and wires 678 and 624 to the rails 515 of section I, thence along rails 515 of section I, and thence by way of the wires 625 and 675, the contact 674, and the contact 604 (Fig. 1), or 804 (Fig. 3), and back to the source by way of the wire 603.

Train apparatus suitable for use with the track apparatus shown in Figs. 1 and 1^A is shown in Fig. 2. The armature 312 of an electromagnet 310 is adapted to tend constantly to cause the production of a warning operation but to be restrained from so doing by the energization of the electromagnet 310, and the armature 313 of an electromagnet 324 is adapted to tend constantly to cause the production of a stopping operation but to be restrained from so doing by the energization of the electromagnet 324. Both of these electromagnets are adapted to be energized by current from a generator 305 on the train when an arm 834 adapted to be moved by the movable part of a polarized relay 831 is, owing to the strength and direction of the current energizing that relay, in such a position that a contacting piece 835 carried thereby bridges two contacts 837 and 838 and enables current to flow from the generator 305 by way of a wire 306, then by way of (a) a wire 309, the electromagnet 310, wires

733 and 841, and the contact 838, and (b) a wire 308, the electromagnet 324, wires 839 and 840, and the contact 837, and thence back to the generator 305 by way of the contacting piece 835 and a wire 307. When current of a predetermined strength less than, and in the same direction as, the current that causes the arm 834 to occupy the last mentioned position energizes the polarized relay 831, the arm 834 is adapted to occupy a position such that its contacting piece 835 makes contact with a contact 836 only and the electromagnet 324 only is energized owing to the fact that whilst a circuit including the electromagnet 324 is completed at the contact 836 in substitution for that broken between the contact 837 and the contacting piece 835, no circuit including the electromagnet 310 is completed in place of the one broken by the separation between the contacting piece 835 and the contact 838; consequently in this case a warning operation is produced on the train whilst the production of a stopping operation is restrained. When no current, or a current whose strength is less than the last mentioned strength, or a current whose direction is opposite to the last mentioned direction energizes the polarized relay no circuit is completed through either of the electromagnets 310 and 324 and both a warning operation and a stopping operation are produced on the train. The polarized relay 831 is adapted to be energized by unidirectional pulsating current from the generator 602 (Fig. 1) on the track, a portion of the current caused to pass along the track rails in the manner hereinbefore described with reference to Figs. 1 and 1^A flowing in the manner now to be described; the electromotive force of the generator 602 is, of course, sufficiently large and the resistance of the train portion of the circuit of the polarized relay 831 sufficiently small to enable the said portion of the current to be large enough to cause the arm 834 to move into the positions hereinafter mentioned. A switch arm 400 is adapted, as by being connected with the reversing gear of the train, to keep contacting pieces 700 and 701 carried thereby but insulated therefrom in contact with contacts 375 and 364 respectively when the train is set for travelling in one direction and in contact with contacts 379 and 378 respectively when the train is set for travelling in the opposite direction. When the switch arm 400 is in the first of these positions—for example when the train is set for traveling in the down direction—and the direction of the current flowing in the track rails from the generator 602 is such as to enable the train to travel in the down direction, current flows from the track rails by way of a contacting means, such as a contacting shoe 820, wires 822 and 823, the contact 364, the contacting piece 701, a wire 829, one terminal 830 of the polarized relay 831, the coils of the polarized relay 831, and the other terminal 832 thereof, a wire 833, the contacting piece 700, the contact 375, wires 826 and 825, and back to the track rails by way of another contacting means, such as a shoe 821; the direction of the current through the coils of the polarized relay is, on account of the agreement between the position of the switch arm 400 and the direction of the current in the track rails, such as to cause the arm 834 to occupy the position in which its contacting piece 835 bridges the contacts 837 and 838 or the position in which its contacting piece 835 makes contact with the contact 836 in accordance with the strength of the current caused in the manner hereinbefore described to flow through the track rails and consequently through the coils of the polarized relay 831; if the current through the track rails is in the opposite direction—i. e., in the direction for enabling trains to travel in the up direction—and the switch arm still occupies the last mentioned position—i. e., the train is set for travelling in the down direction—the current flows in the direction opposite to the last mentioned direction through the coils of the polarized relay 831 and the arm 834 is consequently not moved into either of the aforesaid restraining positions and both a warning operation and a stopping operation are produced on the train. If the switch arm 400 is, in consequence of the setting of the train for the up direction of travel, in the position in which its contacting pieces 700 and 701 are in contact with the contacts 379 and 378 respectively and the direction of the current flowing in the track rails from the generator 602 is such as to enable the train to travel in the up direction, current flows from the track rails by way of the contacting means 821, the wire 325, a wire 826, the contact 378, the contacting piece 701, the wire 829, the terminal 830, the coils of the polarized relay 831, the terminal 832, the wire 833, the contacting piece 700, the contact 379, a wire 927, and back to the track rails by way of the contacting means 820; the direction of the current through the coils of the polarized relay is in this case the same as when the train is set for travelling in the down direction and the direction of the current in the track rails is such as to enable the train to travel in the down direction and consequently the production of a warning operation and a stopping operation, or the production of a stopping operation only, is restrained in the manner hereinbefore described in accordance with the strength of the current caused to flow through the track rails. Thus the currents through the polarized relay are in the direction for causing the restraint of the production of a warning

operation and a stopping operation, or of a stopping operation only, as the case may be, only if the direction of flow of current through the track rails is in agreement with the setting of the switch arm 400, and, if the switch arm 400 be not in the position corresponding to the direction of the current for the time being through the track rails, the current flows through the polarized relay in the opposite direction and both a warning operation and a stopping operation are produced on the train.

Train apparatus suitable for use with the track apparatus illustrated by Figs. 3 and 1^A is illustrated by Fig. 4. The armature 312 of an electromagnet 310 is adapted to tend constantly to cause the production of a warning operation but to be restrained from so doing by the energization of the electromagnet 310 and the armature 313 of an electromagnet 324 is adapted to tend constantly to cause the production of a stopping operation but to be restrained from so doing by the energization of the electromagnet 324. Both of these electromagnets are adapted to be energized by current from a generator 305 on the train when either (a) an arm 943, which is adapted to be moved by the movable part of an instrument 940 adapted to be energized by alternating current and to cause its movable part to change its position in accordance with the strength of the energizing current, is, owing to the strength of the current energizing that instrument, in such a position that a contacting piece 944 carried thereby bridges two contacts 946 and 947 and enables current to flow from the generator 305 by way of a wire 306, then by way of (i) a wire 309, the electromagnet 310, wires 733 and 952, and the contact 947, and (ii) a wire 308, the electromagnet 324, wires 933 and 949, and the contact 946, and thence back to the generator 305 by way of the contacting piece 944, a wire 930, and the wire 307; or (b) an arm 926, which is adapted to be moved by the movable part of another instrument 923 similar in function to the instrument 940, is, owing to the strength of current energizing the instrument 923, in such a position that a contacting piece 953 carried thereby bridges two contacts 929 and 930 and enables current to flow from the generator 305, to the wires 733 and 933 by way of the paths hereinbefore described, thence to the contacts 930 and 929 by way of a wire 936 and a wire 932 respectively, and thence back to the generator 305 by way of the contacting piece 953, a wire 934, and the wire 307. When current of a predetermined strength less than the current that causes the arm 943 of the instrument 940 to occupy the position in which it causes the restraint of the production of both a warning operation and a stopping operation energizes the instrument 940, the arm 943 is adapted to

occupy a position such that its contacting piece 944 makes contact with a contact 945 only and the electromagnet 324 only is energized owing to the fact that whilst a circuit including the electromagnet 324 is completed at the contact 945 in substitution for that broken between the contact 946 and the contacting piece 944, no circuit including the electromagnet 310 is completed in place of the one broken by the separation between the contacting piece 944 and the contact 947; consequently in this case a warning operation is produced on the train whilst the production of a stopping operation is restrained. Similarly when current of a predetermined strength less than the current that causes the arm 926 of the instrument 923 to occupy the position in which it causes the restraint of the production of both a warning operation and a stopping operation energizes the instrument 923, the arm 926 is adapted to occupy such a position that its contacting piece 953 makes contact with a contact 928 only and the electromagnet 324 only is energized owing to the fact that, whilst a circuit including the electromagnet 324 is completed at the contact 928 in substitution for that broken between the contact 929 and the contacting piece 953, no circuit including the electromagnet 310 is completed in place of the one broken by the separation between the contacting piece 953 and the contact 930; consequently in this case a warning operation is produced on the train whilst the production of a stopping operation is restrained. When neither of the instruments 940 and 923 is energized by current whose strength is sufficient to cause the arm 943 or the arm 926 to occupy the position in which it causes the restraint of a stopping operation only, no circuit is completed through either of the electromagnets 310 and 324 and both a warning operation and a stopping operation are produced on the train. The energization of the instrument 940 or the instrument 923 depends upon the frequency of the current caused to flow through the track rails in the manner hereinbefore described with reference to Figs. 3 and 1^A and the direction of travel for which the train is set. A switch arm 400 is adapted, as by being connected with the reversing gear of the train, to keep contacting pieces 700 and 701 carried thereby but insulated therefrom in contact with contacts 375 and 364 respectively when the train is set for travelling in one direction and in contact with contacts 379 and 378 when the train is set for travelling in the opposite direction. When the switch arm 400 is in the first of these positions—for example, when the train is set for travelling in the down direction—it causes the completion of a circuit comprising an induction device 360 that is placed in inductive relation to

the track rails, a wire 361, the contacting piece 701, the contact 364, a wire 938, a condenser 954, a wire 955, one terminal 939 of the instrument 940, the coils of the instrument 940, the other terminal 941 of the instrument 940, a wire 942, the contact 375, the contacting piece 700, and the wire 377; by means of the condenser 954 this circuit is made resonant to the frequency of the current supplied by the generator 702 (Fig. 3) only, so that, unless the frequency of the current is for the time being such as to enable the train to travel in the down direction, the instrument 940 is not energized. If the switch arm 400 is, in consequence of the setting of the train for the up direction of travel, in the position in which its contacting pieces 700 and 701 are in contact with the contacts 379 and 378 respectively, it causes the completion of a circuit comprising the induction device 360, the wire 361, the contacting piece 701, the contact 378, a wire 921, a condenser 956, a wire 957, one terminal 922 of the instrument 923, the coils of the instrument 923, the other terminal 924 of the instrument 923, a wire 925, the contact 379, the contacting piece 700, and the wire 377; by means of the condenser 956 this circuit is made resonant to the frequency of the current supplied by the generator 802 (Fig. 3) only, so that unless the frequency of the current is for the time being such as to enable the train to travel in the up direction, the instrument 923 is not energized. When the instrument 940 or the instrument 923 is energized the position of the arm 943 or the arm 926 depends upon the strength of the current induced in the coil 360 and consequently upon the strength of the current flowing through the track rails, which, in the manner hereinbefore described, is caused to be such as to make the arm 943 or the arm 926 occupy either the position in which it causes the restraint of the production of both a warning operation and a stopping operation or the position in which it causes the restraint of the production of a stopping operation only. Thus the restraint of the production of both a warning operation and a stopping operation, or of a stopping operation only, is effected only when there is agreement between the frequency of the current caused to flow through the track rails and the setting of the switch arm 400.

In the case of the apparatus described with reference to Fig. 2 and with reference to Fig. 4 it will be seen that when current commences to flow through the electromagnet 310 and thus to cause its energization current also flows from the wire 309 by way of a path the completion of which was caused by the last previous de-energization of the electromagnet 310 and which comprises wire 390, a contact 391, a resilient contact 392, a wire 394, a line-clear bell or

buzzer 712, and a wire 395, to the wire 733, and a line-clear indication is thus given, which is caused to cease by the interruption of this path when the armature 312 moves in consequence of the energization of the electromagnet 310 and removes the resilient contact 392 from the contact 391 by moving the arm 393; alternatively the circuit of the line-clear bell or buzzer can be broken after the completion of the circuit of the battery 305 by other means as by pressure of a push button by the driver.

In order to enable the magnet 324 (Figs. 2 and 4) to exercise its restraint while the arm 834 (Fig. 2), or the arm 943 or 926 (Fig. 4), moves from the position corresponding to the greater current strength to the position corresponding to the less current strength hereinbefore referred to and vice versa it may be rendered slow-acting as by providing it with a shunt 710 containing a suitable non-inductive resistance.

When the invention is used in connection with electric trains the current supplied to the track rails for the purposes of the invention should, of course, so differ from the propulsion current as not to be interfered with thereby as far as the operations hereinbefore described are concerned—for example, if alternating or pulsating unidirectional current at one frequency is used for the propulsion, alternating or unidirectional pulsating current at frequencies different from that used for propulsion should be used for the train-controlling currents and train-controlling currents are preferably supplied by means of transformers or induction coils at a higher voltage or voltages than the propulsion current.

I claim:

1. Electrical train-controlling apparatus comprising on a train electro-responsive means adapted when energized by a current of a first strength to give clearance to said train and when energized by a current of a second strength to cause the production of a warning operation on said train and adapted to be caused by the cessation of either of said currents without the production of the other thereof to bring about the production of a stopping operation on said train and receiving means arranged to be in energizable relation to running rails alone and adapted to be caused by currents of two specific different strengths therein to energize said electro-responsive means by currents of said first and second strengths respectively, and, on the track and in connection with three consecutive sections thereof in which the rails of each section on each side of the track are electrically continuous and the rails of each section on one side of the track are separated from adjacent rails by insulation, current-supplying means for supplying the running rails with which said receiving

means is arranged to be in energizable relation on said one side of the track in the first of said three sections with currents of said two specific different strengths and in the second of said three sections with current of the one of said specific different strengths corresponding to current of said first strength, traffic-controlling means pertaining to said second and third sections and adapted (a) in a position corresponding to the clear condition of both said second and third sections to cause said current-supplying means to supply said rails on said one side of said first section with current of the one of said specific different strengths corresponding to current of said first strength, (b) in a position corresponding to the clear condition of said second section and the danger condition of said third section to cause said current-supplying means to supply said rails on said one side of said first section with current of the one of said specific different strengths corresponding to current of said second strength, and (c) in a position corresponding to the danger condition of said third section to cause said current-supplying means not to supply said rails on said one side of said second section with current of either of said specific different strengths.

2. Electrical train-controlling apparatus comprising on a train electro-responsive means adapted when energized by a current of a first strength to give clearance to said train and when energized by a current of a second strength to cause the production of a warning operation on said train and adapted to be caused by the cessation of either of said currents without the production of the other thereof to bring about the production of a stopping operation on said train, and receiving means arranged to be in energizable relation to running rails alone and adapted to be caused by currents of two specific different strengths therein to energize said electro-responsive means by currents of said first and second strengths respectively, and, on the track and in connection with three consecutive sections thereof in which the rails of each section on each side of the track are electrically continuous and the rails of each section on one side of the track are separated from adjacent rails by insulation, train-current-supplying means for supplying the running rails with which said receiving means is arranged to be in energizable relation on said one side of the track in the first of said three sections with currents of said two specific different strengths and in the second of said three sections with current of the one of said specific different strengths corresponding to current of said first strength, track-current-supplying means for supplying the rails on both sides of the second and third sections of

three sections with current that differs from the currents supplied by said train-current-supplying means, traffic-controlling electro-responsive means connected with the rails of said second and third sections respectively and each adapted to be energized only by current from said track-current-supplying means but to be short-circuited from said track-current-supplying means by conductively connected wheels of a railway vehicle in the corresponding section, and means adapted (a) in the case of the energization of both said traffic-controlling electro-responsive means to cause said train-current-supplying means to supply said rails on said one side of said first section with current of the one of said specific different strengths corresponding to current of said first strength, (b) in the case of the energization and non-energization of said traffic-controlling electro-responsive means pertaining to said second and third sections respectively to cause said train-current-supplying means to supply said rails on said one side of said first section with current of the one of said specific different strengths corresponding to current of said second strength, and (c) in the case of the nonenergization of said traffic-controlling electro-responsive means pertaining to said third section to cause said train-current-supplying means not to supply said rails on said one side of said second section with current of either of said specific different strengths.

3. Electrical train-controlling apparatus comprising on a train electro-responsive means adapted when energized by a current of a first strength to give clearance to said train and when energized by a current of a second strength to cause the production of a warning operation on said train and adapted to be caused by the cessation of either of said currents without the production of the other thereof to bring about the production of a stopping operation on said train, and receiving means arranged to be in energizable relation to running rails alone and adapted to be caused by currents of two specific different strengths therein to energize said electro-responsive means by currents of said first and second strengths respectively, and, on the track and in connection with a series of three consecutive sections thereof in which the rails of each section on each side of the track are electrically continuous and the rails of each section on one side of the track are separated from adjacent rails by insulation, current-supplying means for supplying the running rails with which said receiving means is arranged to be in energizable relation on said one side of the track in the first section of said series at each end thereof with currents of said two specific different strengths and in the second section of said series with

current of the one of said specific different strengths corresponding to current of said first strength, traffic-controlling means pertaining to said three sections respectively, 5 adjusting means adapted to be set in two positions and when in said two positions to adapt said traffic-controlling means pertaining to said second and third sections in the two directions respectively (a) in a position 10 corresponding to the clear condition of both of the corresponding second and third sections to cause said current-supplying means to supply said rails on said one side of the corresponding first section with current of 15 the one of said specific different strengths corresponding to current of said first strength, (b) in a position corresponding to the clear condition of said second section and the danger condition of the corresponding third section to cause said current-supplying means to supply said rails on said one side of the corresponding first section with current of the one of said specific different strengths corresponding to current of 20

said second strength, and (c) in a position 25 corresponding to the danger condition of the corresponding third section to cause said current-supplying means not to supply said rails on said one side of said second section with current of either of said specific different strengths. 30

4. Apparatus according to claim 3 comprising on the track means adapted to cause said rails on said one side of the track to be supplied with train-controlling currents 35 differing for the two directions of travel and on said train a direction-corresponding part the position of which depends upon the direction of travel for which said train is set and which is adapted, only when occupying a position agreeing with the current energizing said rails on said one side of the track, to enable clearance to be given to said train. 40

Signed at New York, N. Y., this 28th 45 day of August 1925.

ARTHUR REGINALD ANGUS.
